[57] ABSTRACT

An ammunition handling system is provided for storing rounds of ammunition in an array of parallel columns wherein all of the rounds in the lead column are at all times under the control of and fed by a helical stoker, which subsequently and automatically advances to each column in sequence.

ARTICLE HANDLING SYSTEM

BACKGROUND OF THE INVENTION

1. Field of the Invention

This invention relates to systems for storing and for conveying articles, under control, at high rates; and especially to a linkless ammunition handling system for rate of fire machine guns.

2. Prior Art

Ammunition Handling Systems for linkless ammunition for high rate of fire guns are well known. Examples can be found in U.S. Pat. No. 1,935,914 issued to B. Darsie et al. on May 10, 1960; U.S. Pat. No. 2,993,415 issued to E. W. Panicci et al. on July 25, 1961; and U.S. Pat. No. 3,696,704 issued to L. F. Backus et al. on Oct. 10, 1972. These systems include an outer stationary drum having angularly spaced apart, longitudinally extending partitions therein and an inner, rotating, helical, longitudinally extending partition. Rounds are arranged in longitudinally extending columns about the central longitudinal axis and have their bullets disposed between adjacent layers of the helical partition. Rotation of the helical partition advances the rounds longitudinally along the drum, which rounds are picked up by a scoop disc assembly having traveling sprockets. A drum system not requiring a scoop disc assembly is shown in U.S. Pat. No. 3,800,658 issued to R. A. Hougland et al. On Apr. 2, 1974.

Flat arrays of rectilinear columns of ammunition are shown in U.S. Pat. No. 3,045,553 issued to E. Mosle on July 24, 1962, in which all of the rounds of a given column are fed in sequence before the rounds of the next column in sequence are fed in sequence by an endless conveyor chain.

Flat arrays of rectilinear columns of ammunition are also shown in U.S. Pat. No. 1,136,695 issued to A. Micalus, Jr. on Apr. 20, 1915; U.S. Pat. No. 3,747,469 is issued to E. Ashley et al. on July 24, 1973; and in U.S. Pat. No. 3,720,301 issued to N. C. Garland et al. on Mar. 13, 1973, in which the lead round in each of the columns in sequence is fed by an endless conveyor chain.

In these flat arrays all of the rounds are moved concurrently towards the endless conveyor chain.

SUMMARY OF THE INVENTION

It is an object of this invention to provide an ammunition handling system in a flat rectangular configuration which is relatively simple and rugged in construction.

A feature of this invention is the provision of an ammunition handling system storing rounds of ammunition in an array of parallel columns wherein all of the rounds in the lead column are at all times under the control of and fed by a helical stoker, which subsequently and automatically advances to each column in sequence.

BRIEF DESCRIPTION OF THE DRAWING

These and other objects, features and advantages of the invention will be apparent from the following specification thereof taken in conjunction with the accompanying drawing, in which:

FIG. 1 is perspective view of a first embodiment of this invention having a single, traveling, helical stoker feeding a traveling, endless, conveyor chain;

FIG. 2 is a side view in elevation in cross-section of the embodiment of FIG. 1;

FIG. 3 is a top view in partial cross-section, with the top plate removed, of the embodiment of FIG. 1;

FIG. 4 is a side view of the counter and drive system of the embodiment of FIG. 1;

FIG. 5 is a front view of the counter and drive system of FIG. 4;

FIG. 6 is a perspective view of a second embodiment of this invention having a first traveling helical stoker feeding a second non-traveling helical stoker which in turn feeds an endless conveyor chain;

FIG. 7 is a partial top view of the embodiment of FIG. 6;

FIG. 8 is a right side view of the embodiment of FIG. 6;

FIG. 9 is a front view of the embodiment of FIG. 6; and

FIG. 10 is a detail of a third embodiment of this invention.

A FIRST EMBODIMENT OF THE INVENTION

A flat pack, single helical stoker operated, ammunition handling system is shown in FIGS. 1 through 5. The system includes a top plate 10 to which a plurality of inverted T-shaped rails 12 are fixed in parallel, spaced apart relation to define a plurality of parallel channels 14 of T-shaped cross-section. Each channel 14 is adapted to receive a plurality of cased rounds of ammunition, with the extractor plate 16 of each case interlocked in the cross-slot of the T defined by two immediately adjacent rails 12. In the first embodiment here shown, there are four columns of 23 rounds each. The rounds are held against columnar movement by a left stop bar 17 closing the left end of each channel 14, and by a respective crank arm operated, ball detent 18 closing the right end of each channel.

A right front bracket 20, a right rear bracket 22, a left front bracket 24 and a left rear bracket 26 are respectively fixed to the top plate 10. A right index shaft 28 is journaled through and between the right brackets 20 and 22 as by bearings 30, and a left index shaft 32 is similarly journaled through and between the left brackets 24 and 26. An additional right front bracket 34 is fixed to the bracket 20 and an additional left front bracket 36 is fixed to the bracket 24. A cross-shaft 38 is journaled through and between the brackets 34 and 36. The rear end of the right index shaft 28 is coupled to and driven by a counter and drive system 40, and the front end has a bevel gear 42 fixed thereto and meshed with a bevel gear 44 fixed to the right end of the cross-shaft 38, which has a bevel gear 46 fixed to its left end and meshed with a bevel gear 48 fixed to the left index shaft 32, all to turn the right and left index shafts in synchronism.

An acme screw shaft 50 or a worm shaft is journaled through and between the brackets 20 and 22, and its rear end is coupled to and driven by the counter and drive system 40.

A right traveling bracket 52 is journaled on the right index shaft 28, and a left traveling bracket 54 is journaled on the left index shaft 32. A helical stoker shaft 56 is journaled through and between the brackets 52 and 54. Each index shaft has an irregular helical cam slot 58 therein, in which there rides a cam follower 60 which is fixed to the respective traveling bracket. The slot 58 has a plurality of 90° portions 62 of zero advance respectively in alignment with each channel 14 (or column of rounds), which are intercoupled 630°

portions 64 of progressively slow, rapid and slow advance, whereby two revolutions of the index shafts serve to shift the stoker shaft 56 from alignment with one column of rounds to alignment with the next adjacent column of rounds. The stoker shaft has a helical flute 66 whose radius of curvature is greater than the radius of curvature of the case of the round, so that the flute surface engages the case surface at only two points 68, 70. When driving the rounds to the right to feed the gun the driving point 68 is between the T-shaped rails 12 and the longitudinal axis of the stoker shaft. When driving the rounds to the left to reload the channels the driving point 70 is beyond the stoker shaft axis. A gear 72 is fixed to the right end of the stoker shaft 56 and is meshed with and driven by the acme screw shaft 50.

A turn-around sprocket and conveyor assembly 80 is also carried by the right bracket 52. A two disc, six cup sprocket 82 is fixed on the shaft 84 which is journalled to and between an upper arm 86 and a lower arm 88. An endless chain of conveyor elements 90, such as is shown in U.S. Pat. No. 3,429,221 issued to R. G. Kirkpatrick on Feb. 25, 1969 travels about the sprocket. A curved semi-T-rail 92 is fixed to the traveling bracket 52 and engages the extractor plate of each case as it leaves the T-rails 12 and enters the sprocket 82 and the associated endless conveyor for conveyance to the associated gun or other utilization device.

The counter and drive system 40 is journalled between a front wall 100 and a rear wall 102. Main power is provided to a shaft 104 to which are fixed a gear 106 and a gear 108. The shaft 104 is rotated at the rate of one revolution per round of ammunition pitch. The gear 106 is meshed with a gear 110 fixed to the acme screw shaft 50 which is thereby driven at the rate of eight revolutions per round. The gear 108 is meshed with a one pin geneva drive wheel 112 which is rotated at the rate of one-quarter of a revolution per round on a shaft 114. The wheel 112 drives a six slot geneva driven wheel 116 at the average rate of one-twenty fourth of a revolution per round. The wheel 116 is fixed on a shaft 118 to which is also fixed a one pin geneva drive wheel 120 which drives a six slot geneva driven wheel 122. The wheel 122 is fixed on a shaft 124 to which is also fixed a gear 126. After twenty three revolutions of the input shaft 104 the geneva train provides one-sixth of a revolution of the gear 126 during the twenty fourth revolution of the shaft 104. The gear 126 is meshed with an idler gear 128 fixed on a shaft 130 which is meshed with a gear 132 which is fixed to the right index shaft 28. The one-sixth revolution of the gear 126 provides two revolutions of the index shafts 28 and 32.

In summary, the counter and drive system provides a continuous rotation of the acme screw shaft 50 at a rate of eight revolutions per round; counts out the full complement of rounds in each column which are being extracted therefrom by the helical stoker shaft 56, which stoker shaft is driven by the acme screw shaft; and when the last round, here shown as the twenty-third round, has been extracted from the column and is in the virtual twenty-fourth round position and is still nestled in the flute of the stoker shaft, provides two revolutions to the index shafts 28 and 32. The two revolutions serve to translate the stoker shaft carried by the traveling brackets 52 and 54 to the next adjacent column of rounds together with the last extracted round

of the previous column; i.e. the twenty-third round in the virtual twenty-fourth round position. During this lateral translation, the stoker shaft does not rotate, even though it is meshed with the continuously rotating acme screw shaft, because the rotation of the stoker shaft caused by the translation of the stoker shaft along the longitudinal axis of the acme screw shaft exactly cancels the rotation of the stoker shaft caused by the rotation of the acme screw shaft about its own axis. The 90° of zero advance portion 62 of the index cam slot 58 adjacent each column permits accurate alignment of the stoker shaft notwithstanding some play and tolerance buildup in the index shafts.

The turn-around shaft 84 has a bevel gear 140 fixed thereto which is meshed with a bevel gear 142 fixed to a shaft 144 which is journalled through a bracket 146 fixed to the arm 86 and through the bracket 52 and to which is also fixed a bevel gear 148 which is meshed with and driven by the gear 72.

As mentioned earlier, the conveyor system, which is flexible, and whose input end travels with the stoker shaft from column to column of rounds, may convey the rounds to the associated gun in a conventional manner as shown, for example, in U.S. Pat. No. 3,670,863 issued to O. H. Meier et al. on June 20, 1972. Alternatively, the rounds may be carried to another ammunition handling system as shown, for example, in U.S. Pat. No. 3,696,704 issued to L. F. Backus et al. on Oct. 10, 1972. In any event the rounds may be manually pre-loaded into the T-slot columns individually, or in clips, as discussed with respect to FIG. 10, infra.

A SECOND EMBODIMENT OF THE INVENTION

A variant of the invention employing a fixed auxiliary stoker shaft to collect the rounds from the traveling main stoker shaft and to deliver these rounds to a fixed endless conveyor belt system is shown in FIGS. 6, 7, 8 and 9. In this embodiment there are 26 columns of 47 rounds in channels 200 provided by inverted T-rails 202 integral with a top plate 204.

Power is supplied to the ammunition handling system from an external source, such as the gun, to a power input gear 220 which is fixed to the auxiliary helical stoker shaft 222, which is journalled in suitable stationary brackets, not shown. The gear 220 is meshed with a gear 224 fixed on a shaft 226 and to which is fixed a gear 228. The gear 228 is meshed with a gear which is fixed to the main worm shaft 230, which is journalled in suitable stationary brackets, not shown.

A right indexing screw 240, a left indexing screw 242, and a coupling shaft 244, are respectively journalled in stationary brackets, not shown, and are intercoupled by respective helical gears 246. The coupling shaft 244 extends to the right and has fixed thereto a miter gear 250, which is meshed with a miter gear 252. A pinion 254 is fixedly co-shafted with the gear 252 and is meshed with an idler gear 256, which is meshed with an idler gear 258. The gear 258 is meshed with a gear 260 which is fixedly co-shafted with a pinion gear 262, which is the output gear of the counter and drive system 264.

A worm wheel 266 for synchronizing the discharge conveyor system 267 is meshed with and driven by the main worm shaft 230, and is fixedly co-shafted with a receiving sprocket 268, and a gear which gear is meshed with a gear 270 which is fixedly co-shafted with a gear 272 and a loading sprocket 274. The gear 272

is meshed with a gear 276 which is fixedly co-shafted with a conveyor turn around sprocket 278.

A stoker traveling assembly 279 includes a worm wheel 280 for driving the main helical stoker shaft 282 which is meshed with and driven by the main worm shaft 230, and is fixedly co-shafted with a gear 284 and a stoker transfer sprocket 286. The gear 284 is meshed with a spur gear 288 which is fixedly co-shafted with a helical gear 289. The gear 290 is meshed with a helical gear 292 which is fixedly co-shafted with a gear 294, which is meshed with a gear 296 which is fixedly co-shafted with a gear 298, which is meshed with a gear 300, which is fixed to and drives the main helical stoker shaft 282. The shaft 282 is journaled in suitable traveling brackets 283, respectively riding on the right and left indexing screws 240, 242, and having respective cam followers engaging the cam slots of the indexing screws, as shown with respect to the first embodiment of this invention.

The counter system 264 includes a worm wheel 290 which is meshed with and driven by the main worm shaft 230, and is fixedly co-shafted with a first geneva driving wheel 292 having two pins. The wheel 292 engages a first geneva driven wheel 294 having four slots, which is fixedly co-shafted with a second geneva driving wheel 296 having one pin. The wheel 296 engages a second geneva driven wheel 298 having six slots, which is fixedly co-shafted with a third geneva driving wheel 300 having one pin. The wheel 300 engages a third geneva driven wheel 302 having six slots, which is fixedly co-shafted with a gear 304, which is meshed with the gear 262.

The discharge conveyor system 267, is similar to that shown in U.S. Pat. No. 3,429,221, supra, and includes an endless chain of conveyor elements 310 operating around the turn around sprocket 278. The conventional guides for the conveyor system are not shown.

To retain the rounds in their channel, suitable detents, not shown, are provided at the ends of the channels, as shown with respect to the first embodiment. To retain the rounds against the auxiliary helical stoker shaft 222, a half-T-rail and a pair of endless flexible bands, not shown, are provided. The half-T-rail lies above the shaft 222, as shown with respect to the first embodiment of this invention, and engages the extractor disc of each round of ammunition as it is driven by the shaft 222. One run of one of the flexible bands engages the cases above the stoker shaft along the extractor groove of each case, and the run of the other of the flexible bands engages the cases below the stoker shaft above the neck of each case.

While the right and left indexing screws 240, 242 are here shown as having a uniformly advancing thread, advantageously, they may have the variable thread shown with respect to the first embodiment.

In summary, the input gear 220

1. Provides a continuous rotation of the main worm shaft 230 which in turn:

a. Via the worm wheel 280 drives the main helical stoker shaft 282 and the stoker transfer sprocket 286 to extract seriatim rounds from the adjacent column and to hand them off seriatim to the auxiliary helical stoker shaft,

b. Via the worm wheel 266 drives the loading sprocket 274 and synchronizes the sprockets 268 and 278, which receive the rounds seriatim from the auxiliary helical stoker shaft, and

c. Via the worm wheel 290 drives the geneva train of the counter and drive system 264; and

2. Provides a continuous rotation of the auxiliary helical stoker shaft 222.

5 The geneva train counts out the full complement of the column as they are extracted by the main stoker shaft, and when the last round, here the forty-seventh round, has been extracted from the column and is held by the stoker transfer sprocket 286 in the virtual forty-eighth position, via the coupling shaft 244, provides two revolutions of the right and left indexing screws 240, 242. The indexing screws thereby translate the traveling brackets 283 and the thereto journaled main helical stoker shaft 282 and the transfer sprocket 286

10 15 from a position adjacent the preceeding column to a position adjacent the next succeeding column. During this translation the power worm 230 continues to rotate and cancels out the relative rotation of the therewith meshed worm wheel 280, so that the main helical stoker shaft 282 and the transfer sprocket 286 do not rotate. Thus a lacuna in the train of rounds fed from the shaft 282 to the auxiliary helical stoker shaft 222 is precluded.

20 25 Thus, a continuous, regular train of rounds is extracted from the several columns by the main helical stoker shaft 282 and handed to the auxiliary helical stoker shaft, which passes the train of rounds along to the receiving sprocket 268, which in turn, hands the train of rounds to the loading sprocket 274, which in turn 30 hands the train of rounds into the conveyor elements 310 for delivery to the gun.

35 It may be noted in FIG. 7, that the position shown in solid line of the sprocket 286 shows extraction from the first column of rounds; while the position shown in phantom as 286' shows extraction from the last column of rounds.

The system is reciprocal, and loading of the columns is accomplished by running the power input gear in the reverse direction.

A THIRD EMBODIMENT OF THE INVENTION

As shown in FIG. 10, a full column of rounds 300 may be preloaded into a clip 302 which has inwardly directed feet 304 which enter the extractor groove of the round. The clip 302 is then inserted between a spaced apart pair of inverted T-rails 306, and the rounds are engaged by the main helical stoker shaft as discussed previously.

50 55 What is claimed is:

1. An article storage and feed system, comprising: an array of laterally spaced apart channels, each channel for storing a respective plurality of articles in a respective column along a longitudinal axis, first means for concurrently engaging each of the plurality of articles in any one of said plurality of channels and for sequentially extracting such articles as a train of articles of uniform pitch; second means, coupled to said first means, for translating said first means to each of a plurality of extraction stations in sequence, each of said extractor stations being adjacent a respective one of said plurality of channels; and control means, coupled to said second means, for automatically actuating said second means.
2. A system according to claim 1, wherein: said channels are stationary.
3. A system according to claim 1, wherein:

- said control means counts the number of extraction operations per channel of said first means.
4. A system according to claim 1 wherein: each of said channels includes means for precluding transverse movement of the stored articles and for permitting longitudinal movement of the stored articles; and
- said first means is a first shaft having a helical flute which concurrently engages each of the articles stored in a respective channel, whereby rotation of said first shaft translates the engaged articles longitudinally in said channel.
5. A system according to claim 4 wherein: said second means includes
- traveling support means,
- said traveling support means supporting said first shaft on an axis parallel to the longitudinal axes of said channels, and
- transverse support means,
- said transverse support means supporting said traveling support means for travel along a path transverse to said longitudinal axis.
6. A system according to claim 5 wherein: said transverse support means comprises a pair of spaced apart second shafts, each second shaft having an indential spiral cam track thereon, said spiral having a cycle equal to the space between adjacent channels, each cycle having successive portions of rapid advance, no advance and rapid advance, and
- said traveling support means comprises a pair of brackets respectively paralleled as said second shaft and respectively having a cam follower respectively engaging a spiral cam track, and supporting said first shaft therebetween;
- whereby rotation of said second shafts provides transverse translation of said brackets and said first shaft.
7. A system according to claim 6 further including: a third shaft paralleled for rotation about an axis which is transverse to said array of channels and having a power transmitting thread thereon, power supply means coupled to and rotating said third shaft,
- power receiving means fixed to said first shaft and engaged with said third shaft,
- whereby rotation of said third shaft provides rotation of said first shaft,
- said power receiving means being engaged with said power transmitting thread of said third shaft while said first shaft is translated by said second means.
8. A system according to claim 7 further including: traveling sprocket means carried by said second means for receiving articles in sequence as extracted by said first means.
9. A system according to claim 8 further including: conveyor means for receiving articles in sequence from said traveling sprocket means.
10. A system according to claim 9 wherein: said conveyor means comprises a movable endless chain of conveyor elements for receiving articles in sequence from said traveling sprocket means.
11. A system according to claim 9 wherein: said conveyor means includes
- a fourth shaft journaled for rotation about an axis which is transverse to said array of channels and

- having a helical flute for receiving articles in sequence from said traveling sprocket means.
12. A system according to claim 8 wherein: said control means comprises a counting chain of geneva elements having an output coupled to said second means, and an input operated in synchronization with said first means.
13. A system according to claim 1 wherein: each of said channels comprises:
- a spaced apart pair of guides providing a longitudinally extending slot with a T-shaped transverse opening, and
- a removable, longitudinally extending clip with a C-shaped transverse opening disposed in said T-shaped slot, for receiving a T-shaped projection on each of the articles.
14. An ammunition storage and feed system, comprising:
- an array of laterally spaced apart channels, each channel for storing a respective plurality of rounds of ammunition in a respective column along a longitudinal axis,
- first means for concurrently engaging each of the plurality of rounds in any one of said plurality of channels and for sequentially extracting such rounds as a train of rounds of uniform pitch;
- second means, coupled to said first means, for translating said first means to each of a plurality of extraction stations in sequence, each of said extractor stations being adjacent a respective one of said plurality of channels; and
- a control means, coupled to said second means, for automatically actuating said second means.
15. A system according to claim 14 wherein: said channels are stationary.
16. A system according to claim 14, wherein: said control means counts the number of extraction operations per channel of said first means.
17. A system according to claim 14 wherein: each of said channels includes means for precluding transverse movement of the stored rounds and for permitting longitudinal movement of the stored round and
- said first means is a first shaft having a helical flute which concurrently engages each of the rounds stored in a respective channel, whereby rotation of said first shaft translates the engaged rounds longitudinally in said channel.
18. A system according to claim 17 wherein: said second means includes
- traveling support means,
- said traveling support means supporting said first shaft on an axis parallel to the longitudinal axes of said channels, and
- transverse support means,
- said transverse support means supporting said traveling support means for travel along a path transverse to said longitudinal axis.
19. A system according to claim 18 wherein: said transverse support means comprises a pair of spaced apart second shafts, each second shaft having an indential spiral cam track thereon, said spiral having a cycle equal to the space between adjacent channels, each cycle having successive portions of rapid advance, no advance and rapid advance, and

said traveling support means comprises a pair of brackets respectively paralleled as said second shaft and respectively having a cam follower respectively engaging a spiral cam track, and supporting said first shaft therebetween; whereby rotation of said second shafts provides transverse translation of said brackets and said first shaft.

20. A system according to claim 19 further including: a third shaft paralleled for rotation about an axis 10 which is transverse to said array of channels and having a power transmitting thread thereon, power supply means coupled to and rotating said third shaft, power receiving means fixed to said first shaft and engaged with said third shaft, whereby rotation of said third shaft provides rotation of said first shaft, said power receiving means being engaged with said power transmitting thread of said third shaft while 20 said first shaft is translated by said second means.

21. A system according to claim 20 further including: traveling sprocket means carried by said second means for receiving rounds in sequence as extracted by said first means.

22. A system according to claim 21 further including: conveyor means for receiving rounds in sequence 25 conveyor means for receiving rounds in sequence

from said traveling sprocket means.

23. A system according to claim 22 wherein: said conveyor means comprises a movable endless chain of conveyor elements for receiving rounds in sequence from said traveling sprocket means.

24. A system according to claim 22 wherein: said conveyor means includes a fourth shaft journalled for rotation about an axis which is transverse to said array of channels and having a helical flute for receiving rounds in sequence from said traveling sprocket means.

25. A system according to claim 21 wherein: said control means comprises a counting chain of geneva elements having an output coupled to said second means, and an input operated in synchronization with said first means.

26. A system according to claim 14 wherein: each of said channels comprises: a spaced apart pair of guides providing a longitudinally extending slot with a T-shaped transverse opening, and a removable, longitudinally extending clip with a C-shaped transverse opening disposed in said T-shaped slot, for receiving the extractor disk on each of said rounds.
